United States Patent Office

Des. 193,156
Patented July 3, 1962

193,156

RAILING PANEL

James J.O'Donaughy, 5295 Boundry Road, and James Stewart, 5075 Boundry Road, both of Vancouver, British Columbia, Canada

Filed Oct. 24, 1960, Ser. No. 62,603

Term of patent 3½ years

(Cl. D54—2)

FIGURE 1 is a perspective view of a railing panel showing our new design; and,

FIGURE 2 is a sectional view taken on lines 2—2 of FIGURE 1.

The dominant features of our design reside in the portions shown in full lines on the drawing.

The top right corner of the article has been broken away for convenience of illustration only.

We claim:

The ornamental design for a railing panel, as shown and described.
